(57) **CLAIM**

The ornamental design for a firearm receiver as shown and described.

DESCRIPTION

FIG. 1 is a perspective view of the first embodiment of a firearm receiver, showing our new design;

FIG. 2 is a right-side elevation view of the firearm receiver of FIG. 1;

FIG. 3 is a left-side elevation view of the firearm receiver of FIG. 1;

FIG. 4 is a front elevation view of the firearm receiver of FIG. 1;

FIG. 5 is a rear elevation view of the firearm receiver of FIG. 1;

FIG. 6 is a top plan view of the firearm receiver of FIG. 1;

FIG. 7 is a bottom plan view of the firearm receiver of FIG. 1;

FIG. 8 is a perspective view of the second embodiment of a firearm receiver, showing our new design;

FIG. 9 is a right-side elevation view of the firearm receiver of FIG. 8;

FIG. 10 is a left-side elevation view of the firearm receiver of FIG. 8;

FIG. 11 is a front elevation view of the firearm receiver of FIG. 8;

FIG. 12 is a rear elevation view of the firearm receiver of FIG. 8;

FIG. 13 is a top plan view of the firearm receiver of FIG. 8;

FIG. 14 is a bottom plan view of the firearm receiver of FIG. 8;

FIG. 15 is a perspective view of the third embodiment of a firearm receiver, showing our new design;

FIG. 16 is a right-side elevation view of the firearm receiver of FIG. 15;

(Continued)

FIG. 17 is a left-side elevation view of the firearm receiver of FIG. 15;

FIG. 18 is a front elevation view of the firearm receiver of FIG. 15;

FIG. 19 is a rear elevation view of the firearm receiver of FIG. 15;

FIG. 20 is a top plan view of the firearm receiver of FIG. 15; and,

FIG. 21 is a bottom plan view of the firearm receiver of FIG. 15.

Each figure demonstrates a firearm receiver and various features, surfaces, openings, mounts, contours, and the like as depicted in solid lines. The broken lines in the drawings depict unclaimed portions of the firearm receiver only and form no part of the claimed design.

1 Claim, 21 Drawing Sheets
